UNITED STATES PATENT OFFICE.

CHARLES SHERWOOD FOWLER, OF WESTERLY, RHODE ISLAND.

DESIGN FOR A TEXTILE FABRIC OR THE LIKE.

Application filed January 7, 1926. Serial No. 15,995. Term of patent 3½ years.

To all whom it may concern:

Be it known that I, CHARLES S. FOWLER, a citizen of the United States, and a resident of Westerly, in the county of Washington and State of Rhode Island, have invented a new, original, and ornamental Design for Textile Fabrics or the like, of which the following is a specification, reference being had to the accompanying drawing, forming part thereof.

The figure is a plan view of a textile fabric, showing my new design.

I claim:

The ornamental design for a textile fabric or the like, as shown.

CHARLES SHERWOOD FOWLER.
